[57] ABSTRACT

A web type printing press has a printing cylinder with an impression roll disposed thereabove to provide a nip through which the web passes. Idler rolls, one on each side of the nip, guide the web, tension it and effect its curvature around a portion of the impression roll. The axes of the printing cylinder, the idler rolls and the impression roll are normally parallel. Copy laydown skew adjustment means are provided to move the impression roll to change the angle between its axis and that of the printing cylinder to thereby alter the disposition of the web with respect to the surface of the printing cylinder. This adjustment means compensates for printing errors which would otherwise result from engraving or etching being improperly laid down (i.e., skewed) on the printing cylinder.

SKEW ADJUSTING MEANS FOR PRINTING PRESS IMPRESSION ROLL

BACKGROUND OF THE INVENTION

1. Field of Use

This invention relates generally to web processing machinery and particularly to means therein for correctly adjusting the relationship between the web and processing means on a cylinder therein for performing a repetitive process on the web.

2. Description of the Prior Art

Some web processing machines employ a rotating cylinder which has means thereon for performing a repetitive process or function on a web. In a rotogravure printing press, for example, the rotating cylinder takes the form of a printing cylinder which has engraving in the surface thereof which, when inked, acts against the web, which is backed by an impression roll, to apply an ink pattern to the web. To insure correct disposition of the printed pattern on the web, it is necessary that the web be correctly orientated with respect to the printing cylinder and this is accomplished by idler rollers located in fixed positions with respect to the printing cylinder which guide the web. To insure correct disposition of the pattern on the web, it is also necessary that engraving on the printing cylinder be properly orientated with respect to the axis of the printing cylinder. Normally, the printing cylinder is engraved or etched by a photo-chemical process wherein the cylinder is coated with a photo-sensitive chemical, a photo-negative is affixed to the cylinder, the unit is exposed to light, the photo-negative removed, and the cylinder is then chemically treated to develop the etching or engraving thereon. If the photo-negative was improperly oriented or skewed with respect to the printing cylinder axis, a copy laydown skew error exists which must be compensated for by some means in the press if correct disposition of the printed copy is to result when such a printing cylinder is used in the press.

SUMMARY OF THE PRESENT INVENTION

In accordance with the present invention there is provided a web processing machine, such as a printing press, having an operating roll or a cylinder therein, such as a printing cylinder, with operating means thereon, such as engraving, for performing a repetitive process or function, such as printing, on one side of a continuous web moving through the machine. A backup roll, such as an impression roll, is disposed on the other side of the web and cooperates with the operating roll to provide a nip between which the web passes. Means are provided to guide the web, tension it and to cause it to follow the curvature of a portion of the backup roll. Such means comprise idler rolls, one on each side of the aforesaid nip. In a preferred embodiment, the axes of the operating roll, the idler rolls and, normally, the backup roll are parallel with each other. Skew adjustment means are provided in the machine to adjustably change the orientation of the web with respect to the operating means on the cylinder in the event that such operating means are improperly orientated on the cylinder to insure correct application of such operation means to the web. The skew adjustment means are adjustable to effect movement of the backup roll to change the angle of the axis thereof with respect to the axis of the operating roll to change the disposition of the web with respect to the operating roll. In a

preferred embodiment of the invention, one end of the backup roll is deflectably mounted on the machine frame and the other end is adjustably movable in either direction in a plane which is normal to the common plane in which the axes of the operating roll and backup roll lie.

DRAWINGS

FIG. 1 is an elevational view of a printing cylinder, impression roll and copy laydown skew adjustment means in a printing press in accordance with the invention.

FIG. 2 is a view taken along the line 2—2 of FIG. 1; FIG. 3 is an enlarged view similar to FIG. 2 showing further details; and

FIG. 4 is a top plan view of a portion of the skew adjustment means taken along the line 4—4 of FIG. 3.

DESCRIPTION OF A PREFERRED EMBODIMENT

Referring to FIG. 1, there is shown an elevational view of a portion of a rotogravure type printing press having copy laydown skew adjustment means in accordance with the present invention. The printing press comprises a support frame having spaced apart side plates 10 and 11 between which a supporting member or spacer in the form of a hollow box girder 12 is rigidly connected by bolts 13. Plate 10 is on the drive side of the press and plate 11 is on the operator's side. The side plates 10 and 11 are provided with rigidly connected inwardly extending brackets 13 and 14, respectively. A pair of vertically disposed cylindrical guide pins 15 and 16 are connected between box girder 12 and the brackets 13 and 14, respectively. The guide pins 15 and 16 afford support for bearing housings 17 and 18, respectively, which are mounted thereon and vertically movable or slidable with respect thereto. A main beam 19 is disposed between the bearing housings 17 and 18. Idler arms 20 and 21 are disposed between the ends of main beam 19 and the bearing housings 17 and 18, respectively. Bolts 22 are employed to rigidly secure bearing housing 17, idler arm 20 and one end of main beam 19 together and dowels 23 assure rigidity and accurate alignment of idler arm 20 and main beam 19. Vertical movement of the main beam is carried out by means of actuators 31 which have their housings connected to the box girder 12 and have downwardly extending movable rams 32 which are rigidly connected to main beam 19. The bearing housing 18 and the idler arm 21 are secured to the end of main beam 19 by shoulder screws 24 which take into threaded holes 28 in main beam 19 and permit slight relative horizontal movement between the end of main beam 19 and idler arm 21. A key 25 is disposed in horizontal slots 26 and 27 formed in the end of main beam 19 and in the inner surface of idler arm 21 to insure accurate alignment during beam travel. The shoulder screws 24 are provided with resilient washers 29 such as Belle-ville washers which tend to draw the end of main beam 19 and idler arm 21 together but permit relative movement between the end of the main beam and the idler arm. Dowels 30 assure rigidity and accurate alignment of idler arm 21 and bearing housing 18. Two manually operable threaded lockdown bolts 33 are provided to rigidly secure the end of main beam 19 to idler arm 21 when they are tightened. When loosened, they allow relative movement between beam 19 and idler arm 21.

An impression roll 35 is mounted for rotation on main beam 19 by means of bearing blocks 36 which are secured by bolts 37 to the beam and is vertically movable therewith. A printing cylinder or roll 40 is rotatably mounted below the impression roll and is understood to be suitably supported in a fixed position on the press frame. As FIG. 2 shows, idler members such as rollers 41 and 42 are connected between the idler arms 20 and 21 near the extreme outer ends of the idler arms and serve to guide, tension and effect curvature of a web 44 around a portion of impression roll 35. Web 44, which is to be printed, is threaded around idler roll 42, between the nip between impression roll 35 and printing cylinder 40 and around idler roll 41. The web 44 is movable in the direction of the arrow 46.

In a situation where the etching or engraving laid down on printing cylinder 40 (as by a photochemical etching process using a negative) is correctly disposed with respect to the axis of printing cylinder 40, then it is desired that the axis of impression roll 35, printing cylinder 40 and the axes of the idler rolls 41 and 42 would all be parallel to one another. Furthermore, all of these axes would be normal to the direction of movement of web 44. In a situation where the etching or engraving on printing cylinder 40 is slightly skewed with respect to the axis of the printing cylinder, as a result of incorrect negative placement during the etching process, it is necessary, in order to achieve correct placement of printing on web 44, to move the web very slightly so that its direction of movement is normal to an imaginary line on the surface of printing cylinder 40 which represents the true axial disposition of the etching or engraving on the printing cylinder. The means for accomplishing this in accordance with the present invention are hereinafter described.

As FIGS. 3 and 4 show, relative movement between the end of main beam 19 and idler arm 21 is accomplished by means of a differential screw 46 having an operating wheel 47, which screw has a first threaded portion 48 which makes threaded engagement with a threaded hole 49 in a bracket 50 which is rigidly secured to the end of main beam 19 by a bolt 51. Screw 46 also has a second threaded portion 53 which makes threaded engagement with a threaded hole 54 in bearing housing 18. The differential screw 46 is provided with operating wheel 47 which enables it to be rotated inwardly or outwardly. The threads on portion 53 of screw 46 which engage the hole 54 bearing housing are different in pitch than the threads on portion 48 which engage the hole 49 in bracket 50. A compression type biasing spring 56 is disposed between housing 18 and bracket 50 to inhibit relative movement between those members and prevent rotation of screw 46. Therefore, when differential screw 46 is rotated clockwise with respect to FIG. 1, bracket 50 and the end of main beam 19 rigidly secured thereto are moved toward bearing housing 18. Conversely, counterclockwise movement of the differential screw results in bracket 50 and main beam 19 moving away from bearing housing 18. The other end of the main beam is rigidly secured to idler arm 23 and housing 18, but the beam is able to flex or deflect slightly to allow such movement. The differential screw 46 is provided with a calibration dial 55 which is rigidly secured to screw 46 and which, when moved with respect to a dial pointer 57 rigidly secured to bracket 50, indicates the extent of movement of the end of main beam 19 with respect to idler arm 21. In

practice, such movement would, for example, at a maximum be on the order of ten-thousandths of an inch.

As hereinbefore explained, in normal conditions the impression roll axis, printing cylinder axis and idler roll axes, are all parallel. However, when differential screw 46 is moved, the net result is to cause the axis of impression roll 35 to pivot or deflect in a horizontal plane and to assume a non-parallel relationship with the axes of the idler rolls 41 and 42 and printing cylinder 40. This movement causes web 44 to touch printing cylinder 40 in such a manner that there is a correct printing relationship between the etching or engraving on the printing cylinder surface and the surface of the web being printed.

15

RESUME

A web processing machine, such as a printing press, has an operating roll or a cylinder therein, such as printing cylinder 40, with operating means thereon, such as engraving, for performing a repetitive process or function, such as printing, on one side of a continuous web 44 moving through the machine. A backup roll, such as an impression roll 35, is disposed on the other side of the web and cooperates with operating roll 40 to provide a nip between which the web passes. Means are provided to guide the web, tension it and to cause it to follow the curvature of a portion of backup roll 35. Such means comprise idler rolls, one on each side of the aforesaid nip. In a preferred embodiment, the axes of the operating roll 40, the idler rolls 41 and 42 and, normally, the backup roll 35 are parallel with each other. Skew adjustment means are provided in the machine to adjustably change the orientation of web 44 with respect to the engraving on cylinder 40 in the event that such operating means are improperly orientated on cylinder 40 to insure correct application of such operation means to the web. The skew adjustment means comprise a manually rotatable differential screw 46, which has one set of threads 48 which engage a threaded hole 49 in a bracket 50 rigidly secured to a main beam 19 which supports impression roll 35. Screw 46 has another set of threads 53 (of different pitch than threads 48) which engage a threaded hole 54 in a bearing support 18 on the machine frame. The screw 46 of the skew adjustment means is adjustable to effect movement of backup roll 35 to change the angle of the axis thereof with respect to the axis of operating roll 40 to change the disposition of web 44 with respect to the operating roll. In a preferred embodiment, one end of backup roll 35 is rigidly mounted on the machine frame and the other end is adjustably movable in either direction in a plane which is normal to the common plane in which the axes of operating roll 40 and backup roll 35 lie. Main beam 19 flexes or bends slightly to permit such adjustable movement.

I claim:

1. In a web processing machine:
a support frame,
said frame having threaded means thereon,
an operating roll mounted for rotation on said frame,
a beam mounted on said frame,
one end of said beam being fixed with respect to said frame and the other end of said beam being movable,
said beam having threaded means thereon,
a backup roll mounted for rotation on said beam and cooperating with said operating roll to form a nip,

said rolls having axes which lie on a common plane, at least one idler member mounted on said frame and having an axis parallel to the axis of said operating roll,
 and skew adjustment means including a rotatable 5 threaded member located between said beam and said support frame for effecting deflecting movement of said beam in a plane transverse to said common plane to change the angle of the axis of said backup roll with respect to the axis of said operating roll, said rotatable threaded member including first and second threaded portions of different screw pitch, said first threaded portion on said screw engaging the threaded means on said beam and said second threaded portion on said 10 screw engaging the threaded means on said support frame.

2. A machine according to claim 1 which is a printing press, wherein said operating roll is a printing roll, and wherein said backup roll is an impression roll.

3. A press according to claim 2 wherein said idler member is an idler roll.

4. A press according to claim 2 including at least a pair of idler members, one on each side of said nip formed by said printing roll and said backup roll.

5. In a web processing machine:

a support frame,
 an operating roll mounted for rotation on said frame, first and second spaced apart guide members on said frame,
 first and second bearing housings slidably mounted on said first and second guide members, respectively,
 said second bearing housing having threaded means thereon,
 a beam located between said bearing housings and having a rotatable backup roll mounted thereon cooperating with said operating roll to provide a nip for said web,
 said rolls having axes lying in a common plane,

15
20

25

30
35

40

one end of said beam being rigidly connected to said first bearing housing,
 said beam having threaded means thereon,
 a first idler arm mounted at said one end of said beam,
 a second idler arm located between said second bearing housing and the other end of said beam and rigidly connected to said second bearing housing,
 said other end of said beam being relatively deflectably movable with respect to said one end of said beam,
 at least one idler member connected between said first and second idler arms on one side of said nip, and skew adjustment means between said other end of said beam and said second bearing housing to effect deflecting movement of said beam in a plane transverse to said common plane and with respect to said second bearing housing, said skew adjustment means comprising a rotatable threaded member engageable with said threaded means on said beam and with said threaded means on said second bearing housing.

6. A machine according to claim 5 wherein said rotatable threaded member includes first and second threaded portions of different screw pitch and wherein said first portion engages said threaded means on said beam and wherein said second threaded portion engages said threaded means on said second bearing housing.

7. A machine according to claim 6 including a guide key disposed in registering slots provided in said other end of said main beam and in said second idler arm.

8. A machine according to claim 7 wherein said idler arms support two idler rolls, one roll being provided on each side of said nip.

9. A machine according to claim 8 wherein said machine is a printing press, wherein said operating roll is a printing roll, and wherein said backup roll is an impression roll.
